UNITED STATES PATENT OFFICE.

CLARENCE P. LANDRETH, OF BOSTON, MASSACHUSETTS.

WOVEN BELT.

No. 834,386.

Specification of Letters Patent.

Patented Oct. 30, 1906.

Application filed August 26, 1904. Serial No. 222,227.

To all whom it may concern:

Be it known that I, CLARENCE P. LANDRETH, a citizen of the United States, residing at Boston, county of Suffolk, and State of 5 Massachusetts, have invented an Improvement in Woven Belts, of which the following description, in connection with the accompanying drawings, is a specification, like characters on the drawings representing like 10 parts.

This invention relates to belting, and especially to those classes of belting commonly known to the trade as "canvas" and "woven" belting; and it has for its object to 15 provide a novel belt which will be more effective and more durable than such belts as now commonly manufactured. These canvas and woven belts are commonly made of several plies or thicknesses of material which 20 are secured together either by stitches which extend through all the plies or by means of a binding thread or threads which pass through all the plies.

In both of the above-described forms of 25 belt the binding means is common to all the plies, and therefore they are all bound together by the same binding means. One obvious result of this construction is that after the outer ply of the belt becomes worn suffi- 30 ciently so that the binding-threads are broken the belt as a whole goes to pieces, because after said binding-threads, whether they are in the form of stitches or are put in in the process of weaving, have been broken there 35 is nothing to hold the remaining plies together.

In my improved belting I have overcome 40 this difficulty by binding each ply independently to some other ply or plies, this prefer- ably being done during the process of weaving, so that the binding-threads are part of the threads of the ply itself.

Where each ply is independently bound to 45 some other ply, the wearing away of the outside ply effects only the binding means for binding said outside ply to another ply and does not effect the binding means between the other plies, and therefore after an outside 50 ply has been entirely worn away the remaining plies of the belt are bound together just as firmly as when the belt was new.

Another feature of my invention resides in 55 making a belt of several plies so that the outer ply or plies are more loosely woven than the intermediate plies. A belt having

this construction has a much longer life than where all the plies have the same tension, because in the former case the bending of a thick belt around a pulley does not put the outer plies under an undue tension.

Referring to the drawings, Figure 1 is a top plan view of a belt embodying my invention. Fig. 2 is a section longitudinally of the belt on, for instance, the line *x x*. Fig. 3 is a similar section in a different plane—for instance, on the line *y y*. Fig. 4 is a section on a still different plane—for instance, on the line *z z*. Fig. 5 is a section on the line *a a*. Fig. 6 is a section on the line *b b*. Fig. 7 is a section on the line *c c*. Fig. 8 shows a modified form of the invention, and Fig. 9 shows a portion of a pulley with my improved belt applied thereto.

The belt illustrated in the drawings is a six-ply belt, each ply constituting practically 75 an independent layer of fabric.

For purposes of identification I have designated said plies *a*, *b*, *c*, *d*, *e*, and *f*, respectively. Each ply is formed of the usual warp-threads 3 and weft-threads 4, which are interwoven to form a layer of fabric. As stated above, one feature of my invention relates to the manner in which the several plies are bound or secured together, this being done in such a way that each ply is independently bound to some other ply or plies. In the preferred embodiment of my invention this binding is accomplished by some of the threads which form the ply so bound, and in Figs. 3 to 7 I have illustrated the binding as 90 being accomplished by the warp-threads of the various plies, and in Fig. 8 by the weft-threads.

Fig. 2, which is a section on the line *x x*, shows the separate independent plies of fabric one on the other. Where the binding of the various plies together is accomplished by the warp-threads, I prefer to use certain only of the warp-threads of each ply as binding-threads. In the form of the invention herein 100 illustrated each ply is bound to the adjacent ply, and the binding of plies *a* and *b* together is accomplished by passing certain of the warp-threads in the upper ply *a* below the weft-threads in the ply *b*, as shown in Fig. 3. The binding of the plies *b* and *c* together is 105 similarly accomplished by using certain of the warp-threads in the ply *b* as binding-threads and passing them beneath the weft-threads of the ply *c*, as shown in Fig. 4. 110

Similarly, the binding of the plies *c* and *d* together is accomplished by taking certain of the warp-threads in the ply *c* and passing them under the weft-threads of the ply *d*, as shown in Fig. 5. In the same way plies *d* and *e* and *e* and *f* may be bound together, as shown in Figs. 6 and 7, respectively.

The number of the warp-threads in each ply which it is necessary to use as binding-threads may be varied and will depend upon the number of plies in the belt when completed, the use to which the belt is put, and other similar circumstances.

The binding-threads of the various plies may have any position relative to each other—that is, the binding-threads of the plies may all be in the same vertical plane or each in a different vertical plane, as shown, or the binding-threads for binding the plies *a* and *b* or any other two plies may be in the same vertical plane as those for binding any other two plies together. For the sake of clearness of illustration I have shown the binding-threads in the various plies as situated in different vertical planes; but my invention is not limited to any particular location for these binding-threads.

Another form of my invention is shown in Fig. 8, wherein the binding together of the various plies is done by the weft-threads instead of the warps, and in this embodiment it will be observed that each ply is independently bound to some other ply or plies. The main advantage of this feature of my invention is that the wearing away of the outer ply of the belt will not disturb the binding means for the other plies, as the plies *b* and *c* will be just as securely bound together when the ply *a* is completely worn as they are when the belt was first manufactured.

Another feature of my invention relates to the manner of weaving the various plies to permit a thick belt to be bent back and forth around pulleys without injuring said belt.

Referring to Fig. 9, which shows a portion of the six-ply belt passing over a pulley, it will be seen that the outer ply lies in a circle of larger radius than the other plies, and therefore if all the plies are of the same tension when the belt is straight said outer ply will be subjected to a greater tension when passing over the pulley. The result is that the outer ply of any portion of the belt becomes elongated or stretched when passing around a pulley. When said portion of the belt leaves the pulley in this condition and begins to travel the straight run to the next pulley, the stretched or elongated outer ply becomes slack and all the strain on the belt is taken by the unstretched inner ply or plies. Such inner ply or plies gradually stretch under the strain until they are under substantially the same tension as the other plies, and as a result the whole belt becomes stretched slightly. The next time this same portion of

the belt passes over the pulley the same operation is repeated, the outer ply or plies being still further stretched while passing over the pulleys and the inner ply or plies being subsequently stretched when the portion of the belt leaves the pulley. This alternate stretching of the outer ply or plies and the inner ply or plies continues so long as the belt is used until the limit of elasticity in the material is reached, after which time the plies begin to rupture and the belt becomes unfit for use. I propose to obviate this alternate stretching of the inner and outer plies by so constructing my belt that the outer ply or plies on one or both surfaces of the belt are normally under less tension than the intermediate plies and can therefore readily yield lengthwise without becoming unduly stretched as the belt is passing over a pulley.

The differences in tension between the outer ply and the intermediate ply may be secured by weaving the outer plies more loosely than said intermediate plies or by placing less tension on the warp-threads in said outer plies while they are being woven. I may make one or more of the outer plies on either or both faces of the belt of less tension than the intermediate plies as deemed most effective and according to the number of plies in the belt.

While I prefer to bind the various plies together by threads forming part of the fabric of each ply, yet since I believe I am the first to provide a belt having a plurality of plies with independent binding-threads for each ply I desire to claim this broadly, regardless of the particular way in which the binding is accomplished.

In the drawings each ply is illustrated as being bound to its adjacent ply, but it would still be within my invention to bind each ply to some other ply than the adjacent ply, provided each ply was independently bound to some other ply.

In order to describe my invention, I have illustrated some forms thereof; but I do not wish to be limited to these forms, as the invention is capable of many variations and modifications not herein illustrated.

Having fully described my invention, what I claim as new, and desire to secure by Letters Patent, is—

1. A driving-belt, composed of a plurality of independent closely-woven plies, each ply being bound by a portion only of its own threads to threads which form some other ply.

2. A belt composed of a plurality of independent closely-woven plies, a portion only of the warp-threads of each ply constituting binder-warps and being carried around weft-threads of some other ply.

3. A belt composed of a plurality of independent closely-woven plies, a portion only of the warp-threads of each ply constituting binder-warps and being carried around the

weft-threads of some other ply, said binder-warps being in different vertical planes.

4. A belt composed of a plurality of woven plies, some of which are more loosely woven than others, and each ply being bound by a portion only of its own threads to threads which form some other ply.

In testimony whereof I have signed my name to this specification in the presence of two subscribing witnesses.

CLARENCE P. LANDRETH.
